Inventor.

E. D. Holman.

United States Patent Office.

EDWARD D. HOLMAN, OF BUFFALO, NEW YORK.

Letters Patent No. 66,237, dated July 2, 1867.

IMPROVEMENT IN FRUIT-JARS.

The Schedule referred to in these Letters Patent and making part of the same.

TO ALL WHOM IT MAY CONCERN:

Be it known that I, EDWARD D. HOLMAN, of Buffalo, in the county of Erie, and in the State of New York, have invented certain new and useful Improvements in Fruit-Jars; and do hereby declare that the following is a full, clear, and exact description thereof, reference being had to the accompanying drawing, and to the letters of reference marked thereon.

The nature of my invention consists in the combination of a wire spring with the conical cap or cover of a fruit or preserve-jar and the projecting rib or ring near the top of the same. The drawing, which is in partial section, sufficiently explains my invention.

A is the wire spring; B represents the conical cap or cover; C, a section of the rubber ring, which is usually placed on the under side of such covers; D, the projecting rib, surrounding the neck of the jar.

The cover is fastened by placing the bent ends of the spring over the rib D, as shown at F F, which operation, as will be readily seen, tightens and draws the cap B firmly to the top of the jar, as the spring is being forced along toward the centre of said cap, which, by its form, acts as a wedge to tighten it. The wire A, being elastic, of course holds and keeps the cover firmly in place.

What I claim as my invention, and desire to secure by Letters Patent, is—

The combination of the spring A with the conical cap B and rib D, when constructed substantially as and for the purposes described.

E. D. HOLMAN.
